(57) **CLAIM**

The ornamental design for a tool and parts tray, as shown and described.

DESCRIPTION

FIG. 1 is a perspective view of a tool and parts tray showing my new design;

FIG. 2 is a bottom perspective view of the tool and parts tray of FIG. 1;

FIG. 3 is a top perspective view of the tool and parts tray of FIG. 1;

FIG. 4 is first or left-end elevational view of the tool and parts tray of FIG. 1;

FIG. 5 is a second or right-end elevational view of the tool and parts tray of FIG. 1;

FIG. 6 is a third or left-side elevational view of the tool and parts tray of FIG. 1;

FIG. 7 is a fourth or right-side elevational view of the tool and parts tray of FIG. 1; and,

FIG. 8 is an alternate perspective view of the tool and parts tray as in FIG. 1 showing a plurality of the tool and parts trays stacked in an alternative arrangement.

The broken lines depict environmental structure and form no part of the claimed design.

1 Claim, 6 Drawing Sheets
